U.S. Appl. No. 29/462,060, filed Jul. 30, 2013, Van Deursen.

Primary Examiner — Derrick Holland*Assistant Examiner* — Jennifer O King(74) *Attorney, Agent, or Firm* — Foley & Lardner LLP(57) **CLAIM**

I claim the ornamental design for a portable generator, as shown and described.

DESCRIPTION

FIG. 1 is a front perspective view of a portable generator showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a front perspective view thereof, shown in an alternate environmental configuration.

The broken lines shown represent unclaimed subject matter and form no part of the claimed design.

1 Claim, 9 Drawing Sheets---
